(57) **CLAIM**

The ornamental design for an all-in-one energy storage device, as shown and described.

DESCRIPTION

1. All-in-one energy storage device

1.1 : Perspective

1.2 : Front

1.3 : Back

1.4 : Left

1.5 : Right

1.6 : Top

1.7 : Bottom

FIG. 1.1 to FIG. 1.7 show an all-in-one energy storage device according to the present design; the all-in-one energy storage device is used for storing electric energy.
